UNITED STATES PATENT OFFICE.

HARRY L. BEVANS AND HUGH D. BEVANS, OF MULBERRY, KANSAS.

TIME-CONTROLLED ELECTRIC FIRING-MACHINE.

1,007,177.

Specification of Letters Patent. Patented Oct. 31, 1911.

Application filed May 13, 1910. Serial No. 561,241.

To all whom it may concern:

Be it known that we, HARRY L. BEVANS and HUGH D. BEVANS, citizens of the United States, residing at Mulberry, in the county of Crawford and State of Kansas, have invented certain new and useful Improvements in Time-Controlled Electric Firing-Machines, of which the following is a specification.

10 This invention relates to time controlled electric firing machines for setting off a plurality of blasts in succession, and is especially adapted for use in mines.

The object of the invention is to provide a machine that will operate automatically in such a manner as to close a firing circuit at a predetermined time after the machine has been placed in operation; and a further object is to provide a machine of this character that is adapted to be initially actuated, or started, by means of the control, of an electric circuit by another and similar machine. That is to say, in practicing our invention we employ as many machines as there are blasts to be fired, but all of the machines are operated through one two-wire circuit and their operation is automatic after the first machine has been started.

A further object is to provide an automatic electric signal whereby the operator is kept informed of the sequence of the blasts and of the operation, or non-operation of the apparatus.

The invention is fully illustrated in the accompanying drawings, in which—

Figure 1 is a plan view of one of the time-controlled firing machines, in combination with a circuit diagram for a plurality of blasts, the current source, etc. Fig. 2 is a sectional view, on line II—II of Fig. 1. Fig. 3 is a detail view of a switch-blade, employed in carrying out the invention.

As a preliminary to the description of the machine itself, we shall briefly describe the electric circuit as shown in Fig. 1, wherein 1 designates a power house, in which is located a dynamo 2, or other source of current from which insulated conductors 3, 4 and 5 lead to a mine 6, in which are several chambers, 6a, 6b, 6c, 6d, 6e, 6f, 6g, connected by tunnels or shafts 6h. Within the respective chambers are placed ordinary electric caps, 6h', 6h'',

6h''', 6h'''', etc., connected with the circuit wires 3, 5, by tap wires 7. It is understood that each cap 6h', etc., is embedded in a charge of explosive in any well-known manner. The symbols M', M'', etc., each indicate one of our machines, which are connected to the circuit wires as more clearly shown in the detail portion of the figure. In the power house 1, in series with one of the wires 3, 4, is a signal lamp, 8, and 9 is a manually-controlled switch which is in series with one of said wires. Upon closing the switch, a circuit is closed through the nearest machine, which is shown in detail: starting the mechanism, which after a predetermined time sends current through blast 6h' and machine M', which, after a predetermined time, sends current through machine M'', blast 6h'', and machine M'''. Thus simultaneously with the firing of a blast, the machine which controls the firing of the next blast is started into operation, but causes a time interval to intervene between any two blasts. Where it is desired to greatly increase this interval with respect to a particular chamber, a plurality of the machines are connected as are those marked M'' and M''''; the effect of which will be that the blast 6h'''' in chamber 6d will be fired considerably later than the blast 6h' in chamber 6b.

Now, describing the machine, the same comprises a suitable base 12, on which are mounted a train of gears, a weight for actuating them, a ratchet for restraining and releasing the gears, and a knife switch adapted to be actuated by movement of the gears. The several shafts 13, 14, 15, 16, 17 of the gear train are journaled in cheeks 18 which are mounted on the base 12.

16 is the main or driving shaft, on which are a loose gear 19, a fixed pinion 20, and a winding crank 21; also a fixed ratchet-wheel 22. Fixed to and wound upon this shaft is a cord 23 to which is suspended a suitable weight 24. Gear-wheel 19 meshes with a pinion 25 fixed on shaft 15, on which is fixed a gear 26, meshing with a pinion 27 fixed on shaft 14, on which is fixed a gear 28 which drives a pinion 29, fixed on shaft 13. On the latter is a governor, consisting as shown of several wings or fans 30. The

driving pinion 20 meshes with a gear 31, fixed on shaft 17. The gear wheel 19 carries a stud 32, on which is pivoted a pawl 33 which constantly engages the ratchet-wheel 22, so that the gear 19 shall be driven by the weight 24 through the medium of the ratchet and pawl.

Fixed on the gear wheel 31 is a lug 34, which is normally engaged by a trigger 35, 10 pivoted on a standard 36 and provided with an armature 37, adapted to be attracted by an electromagnet 38, which is fixed to the base.

Fixed upon shaft 17 is a switch blade 39, 15 to which the wire 4 is connected in any suitable way. When the lug 34 is in the position shown, this blade 39 lies between a pair of switch contacts 40, which are both connected to a wire 41 which extends to one 20 terminal of the magnet 38. Fixed on the base 12 in position to receive the blade 39 after a partial revolution thereof, is a second pair of switch contacts 42, which are connected to a circuit wire 5 that leads to a 25 switch blade 39 on the nearest machine M'. The other terminal of the magnet 38 is connected to circuit wire 3 by a tap 43. The switch-blade 39 is insulated from the shaft 17 by a bushing 44, which is preferably 30 square and fits in a square opening in the blade and upon the squared end 17^a of the shaft.

The operation is as follows; assuming that 35 several machines are located as shown in the drawing; and the manual switch 9 is open: The weight 24 of each machine is wound up by rotating the crank 21, the switch blade being now between the switch points 40. The weights 24 tend to drive the switch shafts 17 40 in the direction indicated by arrow, but such movement is prevented by the triggers 35, as the main switch 9 is open and hence the armatures 37 are unattracted by the magnets 38. The circuit through the first blast cap 45 h' is now open, as the switch blade 39 is out of contact with parts 42. Likewise there is no current through any of the caps, h'', h''', h'''', etc. When all is ready for firing the blast h', the operator closes the switch 9, 50 and current flows through the magnet 38 which draws down armature 37 and raises trigger 35, which releases lug 34, whereupon the weight 24 and cord 23 rotate shaft 16 and all the gears, which are caused to move 55 slowly by the governor 30. Ratchet 22 drives pawl 33, gear 19, pinion 20, gear 31, and shaft 17, which slowly moves the blade 39 from points 40 toward points 42, breaking only the magnet circuit, which is immaterial as the lug 34 has passed beneath the trigger 35. As soon as blade 39 forms contact with points 42, current will pass from wire 4 to wire 5, thence through the electric cap h', thence back to the generator through

wire 3, thereby firing the first blast. At the 65 same time, current will pass through the magnet of machine M', which will operate precisely as above described, and will thereby send current through cap h'' and through the magnets of machines M'' and M'''. 70 Machine M'' will, after the interval, energize machine M''', which in turn will fire the cap h'''' and start machine M''''. It is evident that, as long as the circuit through the lamp 8 is closed by any switch blade 39 75 being in contact with its points 40, said lamp will be lighted; and when such blade breaks such contact, said lamp will be extinguished. By watching the lamp, therefore, the operator is advised of the time when each of 80 the machines breaks the magnet circuit. It is also clear that the lamp will be relighted upon the reestablishment of its circuit by the closure of a blade 39 with its points 42, and therefore, if any machine fails to establish 85 such connection, the lamp would remain dark beyond the proper interval, and thus advise the operator of the trouble. The exact machine at fault may be located with certainty by the operator's keeping track of 90 the successive firings, either by tally marks or by inserting pegs in holes in a convenient plate. When the machine M''' closes a circuit through the caps h''' and h''''', both of said caps will of course be fired simultaneously. In like manner, when the machine 95 M'''' in the branch tunnel closes its circuit, the caps h'''' and h''''' will be simultaneously fired. But whenever it is desirable to delay the firing of any cap or caps, a machine is connected to the wires between such caps and to current source. 100

It sometimes happens that the firing of a blast in a mine causes an explosion of gas. If the operator hears such an explosion, he 105 opens the switch 9, thereby preventing any other machine from being started.

Having thus described our invention, what we claim as novel and desire to secure by Letters Patent, is:

1. In combination, a source of current, a firing-circuit connected by one wire directly to the current source, two time controlled firing mechanisms each provided with an automatic switch and with a starting magnet, each of said magnets being connected with said wire; connections through the automatic switch of one mechanism through the starting magnet of the other mechanism, a connection between the opposite pole of the 115 current source and the automatic switch of one of said mechanisms, and a return wire of the firing circuit, connected to the other said mechanism.

2. In combination, a source of current, two 120 time controlled firing mechanisms, each comprising a switch and a starting magnet, a firing circuit, connections between the cur-

rent source, the mechanisms and the firing circuit, whereby one of the mechanisms will be started by the other mechanism after a predetermined interval from the starting of 5 the other mechanism; and a signal lamp in circuit with said current source, the mechanisms and firing circuit, for the purpose described.

In testimony whereof we affix our signatures, in the presence of two witnesses.

HARRY L. BEVANS.
